CLEANSING PREPARATION

Theodore K. Cleveland, Drexel Hill, Pa., assignor
to Philadelphia Quartz Company, Philadelphia,
Pa., a corporation of Pennsylvania

No Drawing. Application May 27, 1931,
Serial No. 540,497

8 Claims.

(CL 87—5)

This invention relates to certain new preparations for cleansing operations as well as to a new method of cleaning, and the principal objects as well as the chief advantages of the invention will 5 be more clearly understood if the following brief reference to the state of the art is first presented.

It is at present recognized in the industries that many of the customary commercial soluble silicates exert a distinct protective effect in controlling corrosion. This is particularly true of the more silicious grades of the customary liquid silicates and the protection afforded is generally attributed to the formation of colloidal films on the surface to be protected, thus preventing access 10 of the attacking agent. As examples where this protective effect has been utilized, there might be mentioned the introduction of soluble silicates into water heating systems or into iron or lead municipal water distributing systems, etc. Small 15 amounts have also been added to shaving soaps, cold creams, etc., which are marketed in metal tubes.

Furthermore, less silicious silicates such as sodium metasilicate are characterized by a much 20 higher effective alkalinity, as well as by variations in their ability to cause deflocculation, emulsification, and the like.

In detergent practice, such factors as time, temperature, concentration, degree of agitation, etc., 25 all have their effect, and each industrial cleaning operation presents a complex of such factors so that the choice of the detergent best suited to the particular operation in hand, is a matter of some nicety.

30 However, even with present knowledge on this subject, it is often difficult to arrive at a choice which is altogether satisfactory. For example, certain cleansing operations may require a silicate of extremely active detergent characteristics, and, therefore, one of high alkalinity. Such a 35 silicate may very well injure the article or substance to be cleaned. At the same time a silicate of less active characteristics may not yield the degree of cleansing which is most desirable. 40 Under circumstances such as these, a compromise is generally resorted to, a silicate of intermediate composition or characteristics being 45 adopted.

I have found, however, that it is possible to 50 prepare a cleansing solution in which is combined the desirable features or characteristics of high alkalinity and great detergent effect with the protective characteristics so necessary in many industrial cleaning operations. I obtain my improved results by preparing mixtures of silicates 55

of different compositions which are dissolved and used for cleaning purposes before their respective constituents have come to a state of equilibrium. This temporary state of non-equilibrium is characteristic of almost all systems in which two different soluble silicates are mixed although it is obvious some combinations are more useful than others. It has not heretofore been realized that such combinations are useful because the art has always assumed that a mixture of two or more silicates would yield a solution having a set of properties intermediate between the properties of its components or that the different properties of the respective silicates entering into the mixture would unfavorably modify one another, 15 or, stated in other words, would defeat the purpose for which the others were used.

Therefore, among the objects of my invention may be cited the following:

The provision of mixtures of alkali metal silicates for cleansing purposes in which the properties of the different silicates are employed simultaneously in the same solution; the provision of a detergent mixture of the character described the action of which may be nicely regulated and 20 predetermined to suit the particular requirements of the contemplated cleansing operation; the provision of cleansing mixtures which will have all 25 of the advantages of strongly alkaline constituents while at the same time embodying the protective characteristics of the more silicious silicates; the provision of dry soluble mixtures of alkali metal silicates of high $R_2O:SiO_2$ ratio with 30 alkali metal silicates of low $R_2O:SiO_2$ ratio where R_2O refers to the oxide of an alkali metal; and, 35 in general, the provision of detergent mixtures of the alkali metal silicates which are adapted for use in cleaning a wide variety of surfaces and materials such as wood, paint, concrete, stone, glass, metals, fibers, textiles, and the like without 40 in any way injuring them while at the same time employing whatever degree of alkalinity may be necessary or advantageous in obtaining the optimum degree of cleansing action.

The foregoing, together with such other objects as may appear hereinafter or are incident to my invention, may be obtained, by way of illustration, according to the following example:

Sodium metasilicate pentahydrate,
 $Na_2SiO_3 \cdot 5H_2O$ ..... 10 lbs. 50
 Soluble sodium silicate having an analysis approximating:
 Per cent
 Na_2O 19.4
 SiO_2 ..... 62.5
 H_2O ..... 18.1 ..... 10 lbs. 55

In the above formula, the $\text{Na}_2\text{O}:\text{SiO}_2$ weight percentage ratio for the metasilicate is 1:0.97; for the more silicious silicate, 1:3.22; and for the mixture of silicates, 1:1.88. The more silicious silicates should be in the form of a fine powder free from lumps. The metasilicate may be used in the customary form available on the market, most of which will pass the U. S. Bureau of Standards 14 mesh screen or even coarser although I prefer to use it in finer form or to grind the two silicates together during or after mixing, thus preventing the tendency for the mixture to separate into coarser and finer fractions. The product is ready for use as a finely comminuted dry mixture by whatever method prepared. This particular mixture is adapted to be put into solution in warm or hot water and used at once, but it is obvious that similar results can be had by mixing the appropriate solutions immediately before use. The example is particularly adapted to such type of service as removing oils, buffing or polishing compositions, milk products, etc., from soft metal surfaces such as lead, tin, copper, nickel, aluminum, zinc, etc., or alloys thereof, or from textiles, wood, etc.

As an example of a mixture in which the action of alkali is still further restrained, I cite the following:

30 Soluble sodium disilicate, of composition approximating:

Per cent		10 lbs.
Na_2O	27.5	
SiO_2	55	
H_2O	17.5	

35 Soluble sodium silicate of composition approximating:

Per cent		10 lbs.
Na_2O	19.4	
SiO_2	62.5	
H_2O	18.1	

40 An intimate powdered mixture is to be made which may be put into solution in warm or preferably hot water and used immediately after dissolving.

45 It is apparent that a series of mixtures each of which comprises basically an alkali metal silicate of relatively low alkali oxide: silica ratio together with a more alkaline alkali metal silicate, can be produced in which from one mixture to the next, the intensity of action may be regulated, either through change in alkali oxide to silica ratio of one or both of the constituents, or by alteration of the relative proportions of constituents used in a given mixture. Such a series of mixtures would be much more widely adaptable to practical problems as they arise than any single silicate.

50 It should be emphasized further that the property of protective action coupled with high activity of alkali which such mixtures exhibit, gradually diminishes after the mixture is put into solution due to rearrangement between the silicates. In time the properties of the mixture in solution become those of a silicate of their aggregate composition and the intermediate $\text{Na}_2\text{O}:\text{SiO}_2$ ratio. Such a single silicate might have been separately prepared and put into solution directly but the advantages which are features of this invention would not be developed.

55 Heating speeds the rearrangement. The most desirable combination of properties is to be expected ordinarily in freshly prepared solutions. Old solutions cannot be expected to be as effective either in action or protection, even though 75 unused.

I wish to point out also that although this invention has been developed around the use of sodium silicates, alkali metal silicates as a class have been mentioned heretofore and may serve the purposes of the invention equally well although, of course, proper allowances are to be made for the individual differences of the specific silicates to be employed.

60 The combination of the more alkaline types of soluble silicates with silicious materials not soluble in water but yielding colloidal silica in contact with alkaline solutions may produce washing solutions not in equilibrium, which are the full equivalent of the silicate mixtures heretofore described. Sodium metasilicate and infusorial earth, tripoli, opaline or other hydrous forms of silica will yield such solutions. They may even be obtained from hydrous clays or other insoluble silicates.

65 The invention contemplates further the use of added materials such as abrasives, caustics, soaps, saponin or other materials which may lend additional desirable characteristics to the products of the invention either for general or specific uses. Powdered rosin may be added in small amounts, which will readily dissolve in the alkaline solutions to form a soap.

70 It should be pointed out that while I prefer to prepare my improved mixtures in the form of a dry powder, yet this, of course, is not essential to obtaining the advantages of the invention as it is quite possible to prepare independent solutions and then bring them together or to add a powder to an already prepared solution. In short, the precise manner in which the materials are mixed is not important, although, as stated, I prefer to provide dry mixtures containing the proper proportions of the ingredients desired which can be made ready for use simply by dissolving them in the proper quantity of water.

75 I also wish to direct attention to the fact that while in most instances the combination of two silicates will be sufficient, yet, it is quite possible to combine more than two should occasion demand.

80 In conclusion, I should like to say that it is well known that silicates which contain more than two molecules of SiO_2 for each R_2O yield solutions characterized by the presence of silica in a colloidal state, and it is believed that this is an important factor in detergent action. Sodium metasilicate and the more alkaline silicates, however, are crystalloidal in character but have useful properties associated with their high alkalinity. It has not heretofore been known that these advantages could be combined in one solution. The range of composition of individual components of these mixtures may extend from sodium hydroxide at one extreme to silica on the other.

85 As a consequence of the high proportion of silica and of buffering and colloidal action induced, the more silicious silicates are less alkaline, that is to say, possess pH values lower than shown by metasilicate or disilicate solutions of equivalent Na_2O concentration. It follows in general that the action of a less silicious silicate on any object subject to attack of alkalis will be greater than that of a silicate with a higher proportion of silica when the Na_2O concentrations are the same. The differences in degree of this action are frequently great. It is in many instances necessary nevertheless to use detergents dependent upon powerful alkaline action in cleaning or other operations even at the risk of some weakening of fiber, etch-

ing or other attack. It is to such operations that the present invention is particularly directed in that it provides a means of obtaining the highly effective detergent or other action of the less silicious alkali metal silicates with the protective action of those containing relatively more silica.

Such a combination of properties is inherent in mixtures such as described. This is due to the fact that although such mixtures possess ratios intermediate between the ratios of the constituent silicates, structural equilibrium between the two to give the properties of a single silicate of the said intermediate composition when put into solution is only slowly attained, each constituent silicate exhibiting in considerable degree and for a period of time the desirable properties for which it was chosen as a component of the mixture. Thus to cite a case, it becomes possible to clean polished aluminum articles with such mixtures and without etching, under conditions and with satisfaction which would not be attainable were either component used singly. The less alkaline silicate would be found inefficient in cleansing action; the more alkaline silicate too strong and likely to ruin the finish. In the mixture the restraining action exerted permits the use of higher temperatures and correspondingly reduced periods under treatment, or in other cases permits the period in contact with solution to be increased as dictated by convenience, for sterilization or for other reasons.

What I claim is:—

1. As a new composition of matter, a dry mixture of sodium metasilicate pentahydrate and a second sodium silicate which if treated separately with water disperses to form a colloidal silicious system.

2. A detergent composition of matter comprising a physical mixture of a crystalline hydrated sodium silicate and a second sodium silicate which disperses in water to form a colloidal silicious system, the relative proportions of said silicates being such as to yield in aqueous solution a detergent bath partaking of the individual characteristics of the said silicates and adapted to be used before equilibrium is attained. 5

3. A detergent composition of matter comprising a physical mixture of a crystalline hydrate of sodium metasilicate and a second sodium silicate which disperses in water to form a colloidal silicious system, the relative proportions of said silicates being such as to yield in aqueous solution 10 a detergent bath partaking of the individual characteristics of the said silicates and adapted to be used before equilibrium is attained. 15

4. A detergent composition of matter comprising a physical mixture of crystalline sodium disilicate and a second sodium silicate which disperses in water to form a colloidal silicious system, the relative proportions of said silicates being such as to yield in aqueous solution a detergent bath partaking of the individual characteristics of the said 20 silicates and adapted to be used before equilibrium is attained. 25

5. An aqueous cleansing solution comprising the composition of claim 1.

6. An aqueous cleansing solution comprising the 30 composition of claim 2.

7. An aqueous cleansing solution comprising the composition of claim 3.

8. An aqueous cleansing solution comprising the 35 composition of claim 4.

THEODORE K. CLEVELAND.
